UNITED STATES PATENT OFFICE

ALBERT TRUTZEL, OF STENDAL, GERMANY, ASSIGNOR TO THE FIRM SCHWARZ-PRESSE, AKTIENGESELLSCHAFT, OF STENDAL, GERMANY

SURFACE-PRINTING, ROTARY SHEET-PRINTING-PRESS

Application filed December 22, 1928, Serial No. 327,880, and in Germany January 2, 1928.

The invention relates to a surface-printing, rotary sheet-printing-press, consisting of two cylinders of equal size, one of which is carrying the negative printing-form, 5 while the other serves as counter-pressure cylinder, whereby the cylinders have been arranged in combination with a swinging furniture, supported by a foldable feeding-table. Arranging and changing of the 10 printing-form can in this type of machines easily be done, as the form is clamped to the cylinder from the front and it is only necessary to raise the feeding-table, carrying the furniture, for placing and exchanging 15 the printing-form. Perfectly clear space is hereby provided for placing the printing-form and injury, or displacement of the furniture by a shock, is perfectly excluded. The machine can easily be operated. 20 Besides, it is very simple in construction, cheap in manufacturing-cost and producing strong prints, as the pressure is not split-up. The negative picture can be transferred upon the printing-form sharp-edged, as the character-picture, made of any kind of material, 25 is directly transferred with the picture-layer upon the layer of the printing-form sensitive to light. Sharp-edged, exact printing-form-negatives are hereby produced, as 30 the thickness of the paper, or any other support receiving the picture, is of no consequence.

The printing-cylinder is fitted with paper-catchers within a recess. The paper is only 35 arranged under vertically disposed furniture. To obtain a softer pressure, two rubber blankets placed upon one another, can be provided instead of the one stretched upon the rubber printing-cylinder, producing 40 thereby a soft support.

The subject of invention has been illustrated in the drawings diagrammatically by way of example.

Figure 1 is a general view of the machine 45 with front shield removed.

Figure 2 illustrates the meshing of the gears provided on the equally large cylinders under relieved pressure.

1 indicates the plate-printing-cylinder carrying the negative printing-form 3 and 2 the

counter-pressure-cylinder with rubber-blanket stretched upon the same. The sheet is arranged against the swinging furniture 4, supported by brackets 10 on the feeding-table 5. The feeding-table 5 is connected with the 55 table-part 15 by hinges and can be moved with the furniture into the position indicated in Fig. 1 by dotted lines. If the printing-form is to be inserted or exchanged, the feeding-table 5 is lifted into this position. 60

At the moment, when catchers 9, on the permanently rotating printing-cylinder, grip the sheet, the furnitures 4 will be deflected and the sheet is passed between the plate-cylinders 1 and the printing-cylinder 2, both being 65 in printing-position, and receives the print from the printing-form or plate 3, which has meanwhile been inked-in by the inking-device 7. The sheet is thereupon removed with the printed side upwards by a chain-lifter 6. Instead of the chain-lifter 6, any other suitable device can be used. The printing-process is 70 repeated at each cylinder-revolution. Relieving the pressure is effected in such a manner, that the eccentric bearing 16, under the 75 influence of the regulating-rod 17, is turned, until both cylinders are brought out of contact. This is however only done so far, that the gears 12 and 13 (Fig. 2), mounted upon the shaft of the cylinders 1 and 2 and firmly 80 connected with the same, are still in engagement. Rotation of the cylinders is consequently not interrupted, so that the position 85 of the two cylinders towards each other, respectively their printing-elements, remains always unchanged.

I claim:

In a rotary sheet-printing press designed for surface printing, the combination of relatively large cylinders of equal size, one carrying the printing form and the other serving as an impression cylinder, of a feed table including a fixed part arranged in spaced relation to said cylinders, and a movable part hinged to the fixed part remote from said cylinders with its free edge positioned immediately adjacent said cylinders for sheet feeding purposes and furniture carried by the free edge of and movable with said movable table part, the hinged mounting of the mov- 90

100

able part permitting such part to be arranged bodily and wholly beyond a vertical plane passing through the hinge in a direction away from the cylinders, the movable part having such length that when swung upwardly on its hinged connection ample space is provided between the fixed part and the cylinders to permit a workman to operate directly on the press.

10 In testimony whereof I affix my signature.
ALBERT TRUTZEL.
